UNITED STATES PATENT OFFICE

REX PENDLETON, OF DALLAS, TEXAS

DESIGN FOR A COMBINATION FLOOR LAMP AND SMOKING SET

Application filed October 25, 1930. Serial No. 37,380. Term of patent 3½ years.

To all whom it may concern:

Be it known that I, REX PENDLETON, a citizen of the United States, residing at Dallas, in the county of Dallas and State of Texas, have invented a new, original, and ornamental Design for Combination Floor Lamp and Smoking Set, of which the following is a specification, reference being had to the accompanying drawing, forming part thereof.

I claim:—

The ornamental design for a combination floor lamp and smoking set as shown.

REX PENDLETON.
